METHOD OF AND MEANS FOR MAINTAINING
SAND BEACHES SMOOTH AND STERILE

Frank B. Hunter, Indianapolis, Ind.

Application August 14, 1933, Serial No. 685,016

10 Claims. (Cl. 4—172)

The present application relates to sand beaches, and more particularly to such beaches as are arranged in proximity to bathing pool installations. It is an object of the present invention to provide a method of, and means for, cleaning, sterilizing, smoothing, and compacting beaches of such characteristics. Further objects of the invention will appear as the description proceeds.

To the accomplishment of the above and related objects, my invention may be embodied in the form illustrated in the accompanying drawing, attention being called to the fact, however, that the drawing is illustrative only, and that change may be made in the specific construction illustrated and described, or in the specific steps stated, so long as the scope of the appended claims is not violated.

Fig. 1 is a plan view of a bathing pool installation embodying the present invention;

Fig. 2 is a fragmentary vertical section of a portion of the installation upon a greatly enlarged scale; and

Fig. 3 is a sectional view of a trap used in connection with my invention upon a still larger scale.

In the past few years, it has been found that the value of a bathing installation is greatly increased where a sand beach is provided in proximity to the pool whereon bathers may loll in the sunshine. The provision of such a beach, however, gives rise to a serious problem of maintaining the beach not only in a sufficiently clean condition to meet the approval of the bathers, but also in sufficiently sterile condition to meet the approval of sanitary boards and the like. It is an object of this invention to solve those problems.

Referring more particularly to the drawing, it will be seen that I have shown a pool 10 which, in the drawing, is illustrated as circular in form, but which may be of any desired form so far as the present invention is concerned. The pool 10 is surrounded by a beach 11, and at spaced points about the periphery of the pool there are provided spreader heads or inlets 12 through which water is supplied to the pool, the outlets for the pool being positioned about the periphery of the island 13 centrally located in the pool.

In the embodiment of my invention illustrated in the present application, the pool is of that character in which the floor 14 slopes gently upwardly toward the periphery of the pool, extending to a rim 15 which is located at a level above the normal level of the water in the pool. Arranged outside of the rim 15 is an annular basin

16 comprising a floor 17 having walls 18 and 19 sloping gently upwardly therefrom, the wall 18 meeting the floor 14 in the rim 15, and the wall 19 terminating at 20 at a level above the normal level of the sand 25 in the basin, but below the level of the rim 15. The portion 20 of the wall 19 separates a gutter 21 from the basin 16, said gutter extending completely around the basin and being provided with one or more drain outlets 23 which may be suitably provided with guards 24. The outer side of the gutter is protected by a wall 22.

At spaced points there are provided beneath the basin 16 a plurality of chambers or traps 26, said traps being substantially filled with sand 27 of a coarser grade than that indicated at 25, or with a mixture of sand and gravel or with gravel alone. A sloping wall 28 extends to a point spaced slightly above the base of each chamber 26 to divide such chamber into two portions, communication between said portions being provided by the space or passage 29 left between the bottom of the wall 28 and the base of the chamber. That portion 26' of the chamber 26 which is separated from the basin 16 by the wall 28 is unoccupied by the filter, and a pipe 30 provides communication between the upper end of said portion 26' and the intake port of a suitable pump 31.

Each of the spreader heads 12 is provided with a port 32 opening into the pool 10 and with a second port 33 opening into the basin 16, and a suitable diverter valve is positioned within the spreader head and is adapted to be controlled by the handwheel 34 to divert water flowing through the head either to the pool 10 or to the basin 16.

Obviously, the floor 17 of the basin 16 will be slightly sloped to drain toward the various traps 26, and preferably a gutter 35 will be formed in such floor to assist in leading water to the respective traps.

It has been found that, in spite of all precautions which may be taken by the operators of a recreational installation of this character, persons who use the pool and the beach will persist in throwing cigarette stubs, cigar stubs, wrappers of various kinds, newspapers, and other trash upon the beach. It is also obvious that, in any public or semi-public installation, the sand of the beach will become contaminated by sputum, mucous, and other excretions of the human body which, in most instances at least, will be germ-laden. It is necessary, therefore, to provide means whereby the beach may be cleaned of visible trash, purged of soluble impurities, and sterilized of germs to

as high degree as may be possible. The visible trash, may, of course, be collected by hand labor, at least to the extent of all such matter which is deposited upon the surface of the sand. Such a procedure is, however, relatively expensive and of course is absolutely ineffective to clean the beach of disease-spreading matter. Furthermore, the human animal in sportive mood invariably takes delight in burying things in sand and much trash is always buried on public beaches during a day's use.

In an installation which is equipped with the apparatus of the present invention, the cleaning and sterilization of the beach is rendered quite simple. After the beach has been cleared of occupants, an attendant or attendants will make a circuit of the beach, manipulating all of the valves 34 to direct water from the spreader heads 12 onto the beach 11. The water which flows through the spreader heads 12 is, of course, the water which is supplied to the pool; and in all modern installations, that water has been treated before it reaches the spreader heads with some sort of sterilizing agent which, in most instances is chlorine. The chlorine-bearing water which is supplied to pools contains sufficient chlorine to be an active sterilizing agent; and the installation necessarily includes means for supplying chlorine to the water supplied to the pool. If desired, the chlorine-supplying means may be accelerated so that the chlorine content of water supplied to the beach for sterilizing purposes will be even higher than the chlorine content normally supplied to the pool.

As water is supplied to the beach, the sand is saturated therewith, the water permeating the whole mass of the sand. As the level of the water rises, it will ultimately reach the level of the rim 20. The operator may now pursue either one of two courses. He may continue the water supply, thereby establishing a current flowing radially outward over the whole surface of the beach 11 and into the gutter 21, or he may stop the water flow at the time when the water level in the beach has been raised substantially to the level of the rim 20. Whichever of these two courses he pursues, he will now preferably agitate the sand 25 as, for instance, by the use of a horse-drawn rake or a plurality of hand-wielded rakes. Such agitation of the sand will, of course, loosen the mass of sand and free any trash which may have been buried in the sand. Paper, cigar butts, cigarette butts, tobacco and other flotsam will rise to the surface of the water and will float there. At the same time, the agitation of the sand will cause much of it to rise in the body of water whence it will settle in a comparatively uniform distribution, thereby materially smoothing the surface of the beach.

If the supply of water to the beach has been continued during the agitation, of course the flotsam will be continually carried off to the gutter 21 as the agitation continues. If, however, the operator has chosen to follow the second of the two above-mentioned courses, very little flotsam will leave the beach until such time as the rakes are withdrawn therefrom and the supply of water to the beach is reinitiated. Upon restarting the supply of water, however, a current will be established, whereby the flotsam will be carried off to the gutter 21.

When the beach has been cleared of flotsam, and clear water is running into the gutter 21, the water supply is shut off and the pump or pumps 31 are started, whereby the traps 26 are evacuated

of water. Obviously, as water is withdrawn from the traps, water will flow from the basin 16 into the traps and will be drawn thence by the pumps 31. Such movement obviously establishes a downward flow of water through the body of sand 25, whereby intimate contact of the chlorine-bearing water with every particle of sand in the whole mass is assured. As the water flows downwardly through the sand mass, the water level in the basin is lowered and, as the water level falls below the normal level of the sand in the basin, the sand will be compacted in the same manner as that in which the sand of the sea shore is compacted.

The result of this treatment will be to leave the sand of the beach in a smooth, compact mass, the surface of the beach cleaned of all flotsam, and the whole mass of sand thoroughly sterilized by the action of the chlorine-bearing water.

I claim as my invention:

1. In combination, a swimming pool, a plurality of inlets spaced about the perimeter of said pool, a sand beach at least partly surrounding said pool and separated therefrom by a wall, a gutter surrounding said beach and separated therefrom by a wall lower than said first wall, means for selectively directing water flowing through said inlets to said pool or to said beach, and means for exhausting water from said beach by downward flow through the sand.

2. The combination with a sand beach, of a gutter located at one edge of said beach, said gutter being separated from said beach by a wall higher than the level of sand on said beach and a water inlet located at the opposite edge of said beach and adapted to establish a flow of water across the surface of said beach to carry flotsam from said beach to said gutter.

3. The combination with a sand beach, of a gutter located at one edge of said beach, said gutter being separated from said beach by a wall higher than the level of sand on said beach and a water inlet located at the opposite edge of said beach and adapted to build up a body of water on said beach to a level slightly above the top of said wall and to establish a current flowing toward said gutter, whereby flotsam on said beach is carried to said gutter.

4. In combination, a basin formed of material substantially impervious to water, water-permeable material partially filling said basin, and a water inlet disposed adjacent the wall defining one edge of said basin, the wall defining the opposite edge of said basin being slightly lower than said first wall.

5. In combination, a basin formed of material substantially impervious to water, water-permeable material partially filling said basin, a water inlet disposed adjacent the wall defining one edge of said basin, the wall defining the opposite edge of said basin being slightly lower than said first wall, a chamber disposed beneath the bottom of said basin and opening therethrough between said walls, and means for exhausting water from said chamber, whereby water standing in said basin is drawn downwardly through said water-permeable material.

6. In combination, an annular basin, one bounding wall of said basin being lower than the other, sand partially filling said basin, a gutter disposed immediately beyond said lower wall, and a plurality of water inlets disposed about said other wall and adapted to supply water to said basin.

7. In combination, an annular basin, one bounding wall of said basin being lower than the other, sand partially filling said basin, a gutter disposed immediately beyond said lower wall, a plurality of water inlets disposed about said other wall and adapted to supply water to said basin, a plurality of chambers, each disposed beneath the bottom of said basin and opening therethrough, and means for exhausting water from said chambers, whereby water standing in said basin is caused to flow downwardly through said sand.

8. The method of cleaning, sterilizing, and smoothing sand beaches which comprises flooding a beach with a liquid sterilizing agent, establishing a flow across the surface of said beach to an outlet whereby flotsam is removed from said beach, and subsequently causing said sterilizing agent to flow downwardly through the sand whereby each particle of sand throughout the mass is intimately contacted by the sterilizing agent, and whereby such sand is compacted.

9. The method of cleaning and smoothing sand

beaches which comprises flooding a beach with a liquid so that the liquid level stands above the sand level, agitating the sand while maintaining such liquid level, whereby flotsam embedded in the sand is dislodged and caused to float upon the surface of the liquid, thereafter establishing a flowing current in said liquid to carry flotsam to an outlet, and thereafter draining the liquid from the beach.

10. The method of cleaning and smoothing sand beaches which comprises flooding a beach with a liquid so that the liquid level stands above the sand level, agitating the sand while maintaining such liquid level, whereby flotsam embedded in the sand is dislodged and caused to float upon the surface of the liquid, thereafter establishing a flowing current in said liquid to carry flotsam to an outlet, and thereafter draining the liquid from the beach, by downward flow through the sand, whereby the sand is smoothed and compacted.
